UNITED STATES PATENT OFFICE

LEON E. LA BOMBARD, OF WALTHAM, AND MELVIN H. SIDEBOOTHAM, OF NEWTONVILLE, MASSACHUSETTS, ASSIGNEES TO SPECIALTY AUTOMATIC MACHINE COMPANY, OF CHELSEA, MASSACHUSETTS, A CORPORATION OF MASSACHUSETTS

COMBINATION PRINTING PRESS

Application filed June 14, 1929. Serial No. 370,854.

This invention relates to printing presses of rotary type, and has particular reference to machines which employ a variable multiplicity of type forms or plates, usually duplicate forms or plates, for printing a travelling web of paper.

In such machines, when the form-carrying cylinder rotates continuously at constant speed and the web of paper is advanced at uniform speed, any plurality of forms carried by the cylinder must be equally spaced around its entire circumference in order to make uniformly spaced impressions on the web. If a portion of the cylinder is uniformly occupied by forms, the web will have undesirable blank spaces. When such a machine is used for printing labels on a web of paper which is to be later cut to provide separate labels, the un-printed areas not only mean waste of paper but also increase the difficulty of properly cutting the web to provide the desired separate labels. The same objection exists in connection with the printing of many articles other than labels.

What is known as an all-size rotary press consists of mechanism which will print uniformly spaced areas on a web regardless of whether or not the entire circumference of the printing cylinder is occupied by forms or plates, but so far as we are aware, no such press has been commercially successful. And what is known as a standard or plain type of rotary press comprises mechanism in which the entire circumference of the printing cylinder carries plates or forms and effects continuous printing on the web.

One of the objects of the present invention is to provide a web rotary press which combines the utilities of both of the above-mentioned types, in that it can be used either as a standard or continuous press, or as an all-size rotary web press.

Another object is to provide a web-printing rotary press capable of making equally spaced impressions on a web of paper regardless of the circumferential area of the printing cylinder that is occupied by plates or forms.

Another object is to provide an improved rotary press having means for varying the

speed of the cylinders so that the feed of the web is started at the slowest speed of the cylinders and continues to travel at the speed of the cylinders throughout the length of the feed.

Another object is to provide an improved rotary press having means for obtaining accurate feeding lengths of the web by moving the web a slight distance after the major feed and printing operations are completed and while the cylinders and feeding mechanism are reaching position to repeat the printing.

With the above-mentioned objects in view, and others hereinafter explained, the invention consists in the construction and combination of parts substantially as hereinafter described and claimed.

Of the accompanying drawings:

Figures 1 and 2 are, respectively, a side elevation and a plan view of so much of the mechanism as is necessary to illustrate our invention.

Figure 3 represents a section on line 3—3 of Figure 2 and looking in the opposite direction from Figure 1.

Figure 4 is a view similar to a portion of Figure 1, on a larger scale, and with the casing or box covers removed.

Figure 5 is a detail perspective view of the pawl carrier.

Figure 6 represents a section on line 6—6 of Figure 4.

Figures 7, 8, 9 and 10 are, respectively, sections on lines 7—7, 8—8, 9—9 and 10—10 of Figure 4.

Figure 11 is a detail perspective view of a portion of one of the gears illustrated in Figure 10.

Figure 12 is a detail perspective view of a lug and pawl member hereinafter described.

Similar reference characters designate similar parts or features in all of the views.

The frame or support for the operating mechanism of the press is illustrated as comprising a base 20 and side wall castings 21. Mounted on one of the wall members 21 is a casing or box 22 hereinafter referred to as the timing box, said box having a removable cover 22'. Mounted on the base 20 is an

other casing 24 having a removable cover 24'. This casing 24 encloses the mechanism for obtaining the variable speed of the shaft 52 as hereinafter described, and will be referred to as the variable speed control box.

From a supply roll not necessary to illustrate, a web of paper P to be printed is drawn in the direction of the arrows (Figures 1, 2 and 3) between upper and lower 10 cooperating printing cylinders 26, 27, the shafts of which have intermeshing gears 28. As any usual inking mechanism may be employed, illustration thereof is omitted.

A bevel pinion 29 carried by the shaft 30 15 of the lower cylinder 27 meshes with a bevel pinion 31 carried by shaft 32 which extends through the box 22 (Fig. 4) and into a bearing 33, and carries a gear 34. A constant speed shaft 35 has a gear 36 (Figs. 3, 4 and 20 7) meshing with an intermediate gear 37 which, in turn, meshes with and transmits motion to the gear 34 and its shaft 32.

The shaft 35 extends into the box 24 (Figs. 4 and 6) and is supported in ball 25 bearings 38, and carries a gear 39 meshing with a pinion 40 carried by shaft 41. The shaft 41 has a large sprocket 42 (Figs. 1, 2 and 3) connected by sprocket chain 43 with a sprocket carried by the shaft of a motor 30 44.

The shaft 35 does not extend through the box 24 as a straight member, but has an off-set or crank or eccentric portion within 35 said box. The said eccentric or crank portion comprises a short shaft 45 (Figs. 4 and 6) one end of which is mounted in the gear 39 eccentric to the axis of the latter, the other end of said eccentric crank shaft 45 being supported by an arm 46 the shaft 40 member 35' of which is supported by a ball bearing 47 in the wall of the box 24.

Mounted on the crank shaft 45 is a gear 48 meshing with a pinion 49 mounted idly on a shaft 50 supported by arms 51 which are 45 hung on an upper shaft 52. The pinion 49 meshes with a gear 53 secured to the shaft 52. Mounted on the crank shaft 45 at one side of the gear 48 is a pitman or link 54 the upper end of which embraces the swingingly-supported shaft 50 which carries the 50 intermediate pinion 49. The purpose of the gearing just described and particularly illustrated by Figures 4 and 6 will be explained hereinafter. Said gearing is capable of being included with the other parts of the machine, or thrown out of gear therewith, by the mechanism which will now be described.

The shaft 52 is in line with the shaft 60 32 but separate therefrom as indicated by dotted lines in Figure 4. Secured to the end of shaft 52 is a clutch disk 55, and projecting from the gear 34 which is carried by the shaft 32, is a clutch disk 56. Between 65 the two clutch disks 55, 56, a clutch sleeve

57 is mounted on the shaft 32 so as to rotate therewith but shiftable thereon along the space between the two clutch disks. A lever 58 is pivotally supported by the frame at 59 and has a roll 60 engaging an annular groove 61 in the clutch sleeve. By means of said lever the clutch sleeve may be shifted to interlock with either the disk 55 of the shaft 52 or with the disk 56 of the shaft 32 to effect a change in the operation 75 of the machine as hereinafter described.

Inside the timing box 22 and secured to the shaft 32 is a spiral gear 62 (Figs. 4, 9 and 10) meshing with a spiral gear 63 secured to a hub or sleeve 64 mounted on a shaft 65 suitable bearings for which are provided in the rear wall and the front cover of the said box 22. Splined on the shaft 65 adjacent to the hub 64 is a ratchet wheel 66 on the hub of which is loosely mounted a wheel comprising a gear-toothed portion 67 and a peripherally smooth rim 68. The arms of said wheel are illustrated at 69 in Figures 4 and 9.

The hub 64 has an arm 70 (Figs. 5, 9 and 10) the upper end of which is widened as at 71 and carries bearing blocks 72 for the trunnions of a rocking member (Fig. 12) having a pawl 73 and a lug 74. The pawl 73 coacts with the teeth of ratchet wheel 66 as hereinafter described, and the lug 74 is adapted to cooperate with a lug 75 projecting from the rim of the gear 67 (Figs. 4 and 11). The said rocking member is so mounted, frictionally, as to remain in either one of the positions to which it is rocked in operation as hereinafter described.

Mounted in a stud 76 (Figs. 8, 9 and 10) projecting from the cover 22' of the timing box is a sleeve 77 having a handle or thumb knob 78 secured to its outer end and a pinion 79 splined on its inner end, said pinion meshing with the gear 67. A pin 80 having a washer 81 at one end and a nut 82 at the other end retains the parts in their relative 105 adjusted positions illustrated by Figure 8.

Mounted in bearings provided in the rear wall and front cover of the timing box 22 is a rock shaft 83 (Figs. 4 and 10) having an arm 84 under the ratchet wheel 66, said arm carrying a pivoted trip 85 normally pressed upward by a spring 86, said trip being in the path of rotation of the lug 74. The rock shaft 83 projects rearwardly from the box 22 (Figs. 3 and 10) and has secured thereto a lever 87 the lower end of which is engaged by a cam 88 carried by the shaft 85, said cam serving to time the operation of the trip 85 as hereinafter described.

The shaft 65 extends through the rear wall of the timing box (Figs. 3 and 9) and has secured thereto a ratchet wheel 89 and a gear wheel 90. A lever 91, pivoted at 92, has a roll 93 at its lower end acted upon by a cam 94 carried by the shaft 35, the up- 130

per end of said lever having a spring-pressed pawl to actuate the ratchet wheel 89. As indicated by dotted lines in Figure 4, a spring extending from the lever 91 to the lever 87, 5 may be employed to effect return movements of the two levers after they have been actuated by the cams.

The gear 90 meshes with a pinion 96 (Figs. 2, 3 and 10) carried by the shaft of 10 the feed roll 97, said shaft being mounted at one end in a bearing 98 at the rear of the box 22 and at the other end on a bearing supported by a stud 99 mounted in a frame upright 100. A brake 101 supported by a 15 stud 102 projecting from the upright 100 (Fig. 10) coacts with a band 103 of the feed roll to check momentum of the feed roll and the mechanism which operates it.

Coacting with the feed roll 97 are a series 20 of pressure disks 104 (Figs. 3 and 10) depending from a cross bar 105 mounted on the box 22 and upright 100. Said cross bar is broken away in Figure 3 and the pressure disks indicated only by dotted lines, in order 25 to avoid obstructing a plain view of the feed roll 97.

The portion 35' of the constant speed shaft 35 projects out from the side wall of the box 24 (Fig. 4) and carries a sprocket wheel 30 which is connected by a chain 106 (Figs. 1, 2 and 3) with a sprocket carried by a shaft 107. As said shaft merely drives ordinary web-re-winding mechanism to roll up the 35 intermittently fed web of paper after the latter has been printed, illustration of such re-winding mechanism is unnecessary.

Having now described the construction of the essential elements of the press, the operation thereof will be explained.

40 When the lever 58 is in the right-hand position as illustrated by Figures 1 and 2, the shaft 52 transmits motion directly to the shaft 32, the mechanism in the box 24 being then included operatively for printing a web in the same manner as what is known as an 45 "all size rotary press"; that is, uniformly spaced printing will be effected regardless of whether or not the entire circumference of the printing cylinder is occupied by forms 50 or plates. For effecting this result, certain 55 adjustments presently explained are made accordingly to the circumferential area of the printing cylinder that is occupied by plates to perform the particular job that is to be done.

When the lever 58 is shifted in the opposite direction so that the clutch sleeve is 60 inter-engaged with the clutch face 56 of the gear 34, the shaft 52 is disconnected so that it can rotate idly, and the drive from shaft 65 35 (the constant-speed shaft) is then transmitted through the gearing 36, 37, 34 to the shaft 32, thereby putting the press into the condition of a standard or plain type of 70 rotary press so that the press can be utilized

when the entire circumference of the printing cylinder is occupied by plates or forms.

An important reason for the variable-speed mechanism such as that illustrated by 75 Figure 6 as in the box 24 is that if the feed of the web were to be absolutely stopped intermittently, especially if the press is to be operated at the usual desired high speed, each start of the web would be liable to cause such a sudden pull on the paper as to 80 tear it. Therefore we provide for picking up the feed when the printing cylinders are at their slowest speed of rotation. This is effected by driving the shaft 52 from the shaft 35 through the mechanism illustrated 85 by Figures 4 and 6, a detailed description of which, and the operation thereof, will now be given:

It is to be understood that the gearing and 90 connections are such that the shaft 52 which (when such shaft is clutched to the shaft 32 drives both the printing cylinders and the web-feeding mechanism) receives its power from the shaft 35 through the mechanism just referred to, and that the object of such 95 mechanism is to effect variable speed movement of the printing cylinders and feed mechanism, with alternating fast and slow speeds. The gear 48 which is connected eccentrically to the shaft 35 will, when rotated, 100 cause the gear 49 to oscillate part way around the axis of shaft 52, because the eccentric relationship described causes a thrust to be exerted through the link 54 against the shaft 50 which carries the gear 49, while the arms 51 hold the gear 49 in mesh with the gear 53 of shaft 52. When this action 105 takes place, the gear 48 rotates the gear 49 and, through the action of the arms 51 and link 54, causes the drive of gear 53 to start 110 slow, then accelerate to maximum and then decrease until there is very slight motion transmitted to the gear 53 and its shaft 52. In other words, part of the rotation of gear 115 48 has but very little rotative effect upon the gear 53 because, while the link and arms are acting to push the shaft 50, the gear 49 is riding partly around the periphery of the gear 53 while imparting little motion to the said gear 53.

From this it will be understood that upon 120 rotation of the gear 48 through its other half of rotation, acting to exert a pull upon the link and arms, the gear 49 is being shifted around the periphery of the gear 53; and since the gear 49 is rotating and is also being moved partly around the axis of gear 53, the speed of rotation of the gear 53 and its shaft which drives the printing cylinders and feed roll, is greatly accelerated. This mechanism therefore causes the printing cylinders and feed mechanism to slow down for a brief period and gradually accelerate and then reduce again.

Assuming that the lever 58 is in the posi- 125

tion illustrated by Figures 1 and 4 so that the variable speed mechanism just referred to is included operatively, and assuming that only one-third of the periphery of the cylinder 26 is occupied by printing plates, the pinion 79 (Fig. 8) will be turned by the knob 78 so that the gear 67 will be adjusted to cause its lug 75 to occupy the position indicated in Figure 4, and the press then started. Both the printing cylinder and the feed roll will rotate at the same surface speed as long as the printing forms contact with the web. After the last form has made its impression, the lug 75 will be in such position that the lug 74 (Figs. 4 and 12) contacts with it and rocks the pawl 73 up out of contact with the ratchet wheel 66. This disconnects the drive from the feed roll 97 and the latter is stopped by its brake 103. The printing cylinders continue to rotate until they reach their slowest speed of rotation due to the described mechanism in the box 24. During the described operation, the rocking member having the lug 74 and pawl 73 continues to be carried around idly until the slowest speed of rotation is reached, which is just as the lug 74 reaches and passes the trip 85, (Fig. 4) and the latter rocks the member so that the pawl 73 re-engages the teeth of the ratchet wheel 66. This causes the feed roll 97 to start revolving at the same surface speed as the printing cylinders. The trip 85 is rocked by the cam 88 acting on the lever 87 to which a spring 35 is connected, so that said trip moves to and from position to act as just described once for each cycle of operation of the printing cylinder. The pawl trip lug 75 is removably connected with the gear 67 by any suitable mounting not necessary to illustrate. To enable the machine to operate on a web traveling at continuous speed, it is only necessary to remove the lug 75, and then the pawl 73 remains constantly in engagement with the ratchet 66.

To produce accurately spaced work, we employ what we term a step feed mechanism which includes the brake 101 and the ratchet wheel 89, and the pawl 95, its lever 91, and the cam 94. If the paper web is to be advanced 20 inches because the plates or forms mounted on the printing cylinder occupy that much of the circumferential area of said cylinder, and effect printing during each rotation or cycle of operation, the gear 67 will be rotatively adjusted so that its lug 75 will occupy a position to coat with the lug 74 of the rocking member in the manner which has been explained, to result in stopping the feed roll. Such adjustment is made that the feed roll will be stopped $\frac{1}{8}$ of an inch short of the 20 inches desired. The brake 101 prevents over-throw of the feed roll beyond this point, but the brake 65 can not be relied upon to effect accurate reg-

ister, consequently the feed is stopped, as just explained, after 19 and $\frac{7}{8}$ inches of paper is fed and while the printing cylinders and the pawl 73 are completing their cycle. Then, timed to operate during the slow speed of travel of the cylinders, the cam 94 acts on the lever 91 to cause the pawl 95 to advance the ratchet 89 and, through the gearing and connections described, cause the periphery of the feed roll to be advanced $\frac{1}{8}$ of an inch, thus completing the 20 inch feed desired.

Having now described our invention, we claim:

1. A web-printing rotary press having printing cylinders and web-feeding mechanism, means for accelerating and reducing the speed of operation of said cylinders and feeding mechanism during each cycle of printing operation, and means for imparting a slight advance movement to the web prior to the start of each successive cycle of printing operation.

2. A web-printing rotary press having web-feeding mechanism and having means for driving the printing and web-feeding mechanisms at continuous speeds, said press including means for driving the printing and feeding mechanisms at varying speeds during each cycle of operation.

3. A web-printing rotary press having web-feeding mechanism and having means for driving the printing and web-feeding mechanisms at continuous speeds, said press having means for stopping the web of paper during each cycle of operation.

4. A web-printing rotary press having web-feeding mechanism and having means for driving the printing and web-feeding mechanisms at continuous speeds, said press having means for stopping and starting the web of paper and the printing mechanism during each cycle of operation.

5. A web-printing rotary press having web-feeding mechanism and having means for driving the printing and web-feeding mechanisms at continuous speeds, said press having means for starting and stopping the printing mechanism during each cycle of operation.

6. A web-printing and rotary press having web-feeding mechanism and having means for driving the printing and web-feeding mechanisms at continuous speeds, said press having means for varying the speed of travel of the web of paper during each cycle of operation.

7. A web-printing rotary press having web-feeding mechanism and having means for driving the printing and web-feeding mechanisms at continuous speeds, said press having means for varying the speed of the printing cylinder during each cycle of operation.

8. A web-printing rotary press having

web-feeding mechanism and having means for driving the printing and web-feeding mechanisms at continuous speeds, said press including means for driving the printing and feeding mechanisms at varying speeds during each cycle of operation and also including two alternatively operative sets of gearing for controlling said speeds.

9. A web-printing rotary press having web-feeding mechanism and having means for driving the printing and web-feeding mechanisms at continuous speeds, said press including means for driving the printing and feeding mechanisms at varying speeds during each cycle of operation, said machine including two alternatively operative sets of gearing and a shiftable clutch mechanism for controlling said speeds.

In testimony whereof we have affixed our signatures.

LEON E. LA BOMBARD.
MELVIN H. SIDEBOOTHAM.
